distance to permit the arm 22 to clear the bearing pin 20 of the brush thereby permitting the brush to be vertically removed from the casing. However, due to the offset portion 25 of the lever and 5 due to the fact that this offset portion is so spaced from the end wall of the housing, the lever cannot be, under normal circumstances, moved a sufficient distance laterally to release the brush. This can only be done when the lever is swung 10 outwardly far enough to permit the offset portion to pass through the slot 28 and it will be noted that the slot 28 is sufficiently wide to permit this offset portion to move therethrough. Due to the fact that the arm 22' is longer than the arm 22 15 even when the lever 21 is moved to clear the arm 22, the arm 22' will still remain in a receiving position. Therefore, when the brush is inserted it will drop down on the arm 22' and cannot drop past the lever. This insures the brush being re- 20 inserted in the same position as when removed and also facilitates the insertion of the brush in position.

In the structure illustrated in Fig. 4, the construction is substantially the same as that illustrated in Fig. 2 with the exception that lever 21 is provided with bifurcated arms 22 and 22' of equal length. This construction is somewhat cheaper than that illustrated in Fig. 2. It does, however, provide the laterally displaceable lever 30 arm having an end slot or a pair of arms embracing the pivot member of the brush as shown in Fig. 2.

I claim as my invention:

1. A carpet sweeper comprising a casing having 35 end walls, a brush spindle mounted in said casing and extending through slots in said end walls, brush driving wheels for said spindle mounted on said end walls, a housing for said wheels secured on said end walls and having end and side walls 40 and a mounting for said brush spindle secured to the end wall of each housing comprising a lever having a spindle receiving notch at its inner end embracing said spindle, a pivot on the end wall of said housing on which said lever is pivotally and 45 slidably mounted, a slot in said walls of said housing having rack teeth on one wall thereof, one end of said lever projecting through said slot and engaging said teeth to maintain the lever in any of its adjustable positions, and a stop on said lever 50 adapted to normally abut said end wall of said housing to prevent lateral displacement of said lever.

2. A carpet sweeper comprising a casing having 55 end walls, a brush spindle mounted in said casing and extending through said end walls, brush driving wheels for said spindle mounted on said end walls, a housing for said wheels secured to each of said end walls, having end and side walls and a mounting for said brush spindle secured to the end walls of said housing comprising a lever having a spindle receiving notch at its inner end embracing said spindle and an elongated slot therein, a headed pivot pin on said housing end wall extending through said slot and 60 having its head bearing on said lever to provide a pivotal and sliding mounting for said lever, a slot

in the side wall of said housing having rack teeth on one wall thereof, one end of said lever being offset to form a shoulder and projecting through said slot and adapted to engage by the elasticity of the lever with said rack teeth, said shoulder forming an abutment member to formally engage the side wall of the housing and prevent lateral displacement of the lever. 5

3. A brush mounting for carpet sweepers having a housing provided with end walls, comprising a supporting lever having bifurcated arms at one end thereof spaced apart to receive the brush spindle therebetween, one of said arms being of greater length than the other, a pivot for said lever mounted on an end wall of the carpet 15 sweeper housing, said lever having an elongated slot therein extending longitudinally of the lever and receiving said pivot to permit longitudinal movement of the arm on the pivot, and rack teeth on a portion of the carpet sweeper housing 20 adapted to be engaged by the end of said lever for maintaining the same in any adjusted position.

4. A brush mounting for carpet sweepers having a housing provided with end walls, comprising a lever having a bifurcated end to receive a brush spindle between the arms thereof, the upper of the bifurcated arms being longer than the lower arm, said lever having a longitudinally extending elongated slot formed therein, a pivot 30 pin extending through said slot, the housing of the sweeper having in an end wall thereof an opening provided with rack teeth on one of the side walls thereof, the free end of the lever having an offset portion adapted to extend through said opening and the offset providing an abutment to normally engage the portion of the housing to prevent transverse displacement of the lever a sufficient distance to disengage said bifurcated arms from said spindle. 40

5. A brush mounting for carpet sweepers having a housing provided with end walls, comprising a lever having a bifurcated end, a pivot for said lever, an elongated slot in said lever extending longitudinally of said lever for receiving said pivot to permit transverse movement of the lever on said pivot, the free end of said lever having a portion extending at right angles thereto and a handle portion projecting from said bent portion and extending substantially parallel with 50 the lever, said sweeper housing having an opening therein of sufficient width to permit the passing therethrough of said bent portion and having rack teeth on one of the side walls thereof. 55

6. A mounting for carpet sweeper wheels comprising a sheet metal plate having a struck up pocket formed therein with one end open and a struck up strap formed on said end plate, a spindle supporting bar having one end extended into said pocket and the opposite end passing beneath said strap, the end entering the pocket being narrower than the width of the pocket to permit a vertical movement thereof, and a spindle for the 60 sweeper wheel mounted on said bar. 65
